Letters Patent No. 1825 Dated Oct 6, 1868.

Antedated July 7, 1868
Design for Blind Binding.

Form

The schedule referred to in these Letters Patent and making part of the same.

~~~~~

To all whom it may concern:

Be it known that I, H. W. Glensel of the City and County of Philadelphia, State of Pennsylvania, have invented or produced a new and original design for a blind binding; and I do hereby declare the accompanying drawing, with the following explanation of the same, to form a full, clear and exact description of the said design.

The drawing represents sufficient of a strip of blind binding to illustrate my new design.

The figure A, consists of two scrolls, formed and arranged in the manner clearly shown in the drawing; the said figure A, being situated at such distances apart as to almost enclose, between the ends of the scrolls, the lozenge shaped figure B.

Irrespective of the materials and colors used in the production of the design, and irrespective of the edging shown, I claim the ornamental figures and forms
